CIRCUIT INTERRUPTER

Edward F. Beck, Pittsburgh, Pa., assignor to
Westinghouse Electric & Manufacturing Com-
pany, East Pittsburgh, Pa., a corporation of
Pennsylvania

Application August 25, 1933, Serial No. 686,765

29 Claims. (Cl. 200—123)

My invention relates to circuit interrupters and particularly to cutout devices for protecting equipment such as distribution transformers.

Protective equipment for apparatus of this type is required to perform two main functions: First, it should reliably and positively interrupt the controlled circuit upon the occurrence of predetermined overload conditions, regardless of the magnitude of the overload. And, second, it should in some manner readily indicate to a maintenance operator that the cutout has functioned, this last being especially important when the devices are used to protect pole mounted transformers or the like, because it is desirable that the operator be able to ascertain whether a cutout has functioned without having to climb the pole. In addition to the above functional requirements, a satisfactory device of this type should be easy to install and must be relatively inexpensive, due to the large numbers which are used on even a moderate size distribution system.

It is an object of my invention, therefore, to provide an improved electrical cutout that shall be simple in design, reliable in operation, and inexpensive to manufacture, and that shall be capable of readily indicating when it has operated to open the controlled circuits.

It is also an object of my invention to provide an improved cutout that shall be entirely mountable upon one of the line conductors of a transmission system, and that shall include means for producing an explosive blast of out-flowing gas for extinguishing the arc during the circuit interrupting operation.

A further object of my invention is to provide a novel heating means for causing the operation of thermally responsive devices, my novel heating means to include an electro-responsive device for controlling the heating effect thereof in accordance with circuit conditions.

A further object of my invention is to provide an improved circuit interrupting device that shall include a frangible closure, and electro-responsive means within the frangible closure for creating pressure to effect the opening of the controlled circuit.

A still further object of my invention is to provide a novel circuit interrupter, having movable contact means biased to the open circuit position and an improved electro-responsive means for holding the interrupter closed against the action of the biasing means.

These and other objects of my invention will be more clearly understood from the following de-

scription of a preferred embodiment of my invention.

Referring to the drawing:

Figure 1 is an elevational view of a cutout embodying the principal features of my invention.

Fig. 2 is a sectional view of the cutout shown in Fig. 1, on the line II—II of that figure.

Fig. 3 is a sectional view on the line III—III of Fig. 2.

Fig. 4 is a sectional view on line IV—IV of Fig. 2.

Fig. 5 is a detail view showing the conducting member disposed in the lower portion of the cutout shown in Figs. 1 to 4.

Fig. 6 is a sectional view on the line VI—VI of Fig. 5.

Figs. 7 and 8 are detail views showing the conducting plate which cooperates with the member shown in Figs. 5 and 6, and

Fig. 9 is a fragmentary perspective view showing two of the cutouts illustrated in Figs. 1 to 4 in use with a distribution transformer.

As shown in the drawing, the preferred embodiment of my invention comprises a metallic cap member 1, and a porcelain insulating member 3 having a tubular passage 5 therein for containing the other elements of the device. The porcelain insulating member 3 is cemented to the cap member 1 by means of suitable cementing material 7. An annular washer 8 of cork or like material is interposed between the upper edges of the insulating member 3 and the cap member 1 in order to make a gas tight connection and to prevent undue strain being placed on the insulating member during the cementing process. The cap member 1 is provided with an up-standing portion 11 formed integral therewith. This portion 11 has a threaded opening 13 and two recesses 15 and 17 machined therein, and is adapted to cooperate with a clamp member 19 to permit the device to be connected to one of the conductors of a transmission line. The bolt 21 and the lock washer 23 provide a convenient means for readily connecting and disconnecting the cap member 1 from the line conductor.

The lower portion of the tubular passage 5 is partially closed by an annular shoulder 25 which is formed integral with the insulating member 3. This annular shoulder 25 serves as a retaining means for holding the electro-responsive heating means used in this embodiment of my invention within the passage 5. In addition, it provides a convenient means for restricting the area of the opening through which the gases formed within the device during the circuit in-

terrupting operation are vented thereby increasing the arc extinguishing capacity of the device.

One end of the flexible conductor 27, which is used for completing the electrical circuit from the interrupter to the controlled apparatus, is soldered in the recess 31 provided in the conducting member 29 (shown particularly in Figs. 5 and 6). The conducting member 29 is adapted to be supported in the central opening 33 in the annular portion 25 of the insulating member 3 by means of a fusible alloy 35 disposed therein. The edge portion 37 of the conducting member 29 cooperates with the alloy 35 and the annular portion 25 of the insulating member to effectively seal the tubular passage 5 within the cutout, thereby forming a closed gas-tight chamber.

A metal plate 39 having a dished portion 41 and a centrally disposed opening 43 (Figs. 7 and 8) is positioned immediately above the annular base portion 25 of the insulating member 3. Immediately above this plate are three conducting plates 45 (Fig. 4), which are preferably of a non-metallic resistance material such as carbon or a solid agglomerate consisting chiefly of silicon carbide. A circular metal plate 47 is disposed above the three non-metallic resistance plates 45, and is electrically connected to the cap member 1 by means of a flexible shunt 49, one end of which is brazed or otherwise conductively joined to each of the two connected members. A fusible link 51 is conductively joined to the upper metal plate 47 and the lower metal plate 39, and serves to provide a conducting path through the cutout which is electrically in parallel with the conducting path provided by the three resistance disks 45.

A high temperature solder is used for fastening the end of the flexible conductor 27 to the conducting member 29. For holding the conducting member 29 in the passage 33 within the lower portion of the insulating member 3 and for completing the electrical circuit from the conducting member 29 to the lower plate 39, I prefer to use a low temperature lead-tin alloy, the proportions of which closely approximate the proportions of the eutectic alloy of those metals. These alloys have very sharp melting points, usually in the neighborhood of 80 to 100° C. and permit very accurate calibration of any thermally responsive device wherein they are used.

The remainder of the tubular passage 5 within the porcelain insulating member 3 is preferably filled with a halogenated wax 48 having a melting point somewhere in the neighborhood of 100° C. These waxes are readily vaporizable upon the application of heat to form large quantities of gas which, when properly directed, may be utilized for extinguishing an electric arc, and at the same time, when the waxes are cold they have considerable mechanical strength, thereby serving to securely hold the various parts of the device within the tubular space 5.

The electrical circuit through the cutout is comparatively direct: Beginning with the upstanding portion 11, which is adapted to be conductively joined to one of the conductors of a transmission line by the clamp member 19, the current flows successively through the cap 1 itself, the flexible conducting member 27 disposed within the tubular insulating member 3, thence through the parallel path formed by the three flat disks 45 of resistance material and the fusible element 51 to the lower conducting plate 39, and

finally through the fusible alloy 35 intermediate the lower conducting member 39 and the conducting member 29 to the flexible conductor 27. The flexible shunt 49 is of sufficient length that the various parts of the device may be entirely assembled within the insulating member 3, the wax 48 poured in, and the upper end of the shunt 49 then connected to the inside of the cap member 1; the remaining steps being the placing of the insulating member 3 within the cap 1 and the pouring in of the cement 7.

It will be noted, as shown particularly in Fig. 4, that the porcelain insulating member 3 is provided with a section 53 of restricted cross sectional area disposed immediately adjacent the lower resistance disk 45. This section 53, as will be explained later, permits the insulating member 3 to be broken when the pressure within the device reaches a predetermined point, and also serves to permit the insulating member to be broken by local heating, to cause the interrupter to open the controlled circuit.

The weight of the flexible conducting member 27, which is used for connecting the cutout to the controlled apparatus, is depended upon to provide a biasing force tending to separate the conducting means which are mounted on either end of the tubular insulating member 3, that is, the cap 1 and the conducting member 29.

The operation of my invention is substantially as follows: Upon the occurrence of a moderate overload which is of just sufficient magnitude to cause the fusing of the fusible element 51 connected in parallel with the three resistance disks 45 all of the current carried by the device must flow through these disks and thereby generate heat. The immediate result is to heat the lower conducting plate 39 and if the overload continues for a sufficient period of time, it will ultimately result in the fusion of the low temperature alloy 35 intermediate the conducting plate 39 and the conducting member 29 fastened to the flexible conductor 27. The fusing of the alloy 35 will then permit the biasing effect of the weight of the flexible conductor 27 to move the conducting member 29 out of the opening 33 within the lower end of the insulating member 3, thereby opening the circuit. Since the flexible conductor completely disengages the cutout during the circuit interrupting operation, a maintenance operator standing on the ground may readily ascertain that the device has operated without having to climb the pole or other supporting structure.

Upon the occurrence of a somewhat larger overload which is capable of causing very rapid fusion of the fusible link 51, one of two things may take place. Either the low temperature fusible alloy 35 intermediate the lower conducting plate and the conducting member 29 fastened to the flexible conductor 27 will melt, thereby permitting the circuit to be opened by the falling of the flexible member, as described above, or sufficient local heating of the reduced area section 53 of the porcelain insulating member 3 will result to cause that member to break, thereby permitting the entire end portion of the insulating member to fall, thereby opening the circuit. This breaking of the porcelain member 3 results from the fact that porcelain has a sufficiently high coefficient of thermal expansion that localized heating if brought about with sufficient rapidity, will invariably cause the porcelain to break.

Upon the occurrence of very heavy overloads or short circuit conditions in the protected appara-

tus, the fusible link 51 will melt practically instantaneously. The fusing of this member will probably result in the formation of an arc which is of too large a magnitude to be entirely extinguished due to the conducting path in parallel therewith (the three resistance disks 45). Thus, while a considerable portion of the overload current will flow through the resistance disks 45, there will be an arc within the tubular passage 10 formed by the walls of the insulating member 3. This arc will act upon the halogenated wax 48 or other compound which is disposed therein and will cause immediate volatilization of a considerable quantity of that wax or other compound. If 15 this volatilization proceeds at a sufficiently rapid rate, the pressure within the chamber formed by the insulating member 3 and the cap member 4 will cause the insulating member to break adjacent the section 83 of reduced cross sectional 20 area, thereby causing the entire lower portion of the tubular insulating member 3 to be expelled from the remainder of the device with considerable force. The out-flowing blast of gas from the interior of the cutout, which will follow the rupture of the frangible closure 3, will materially aid in extinguishing the arc and thereby interrupting the controlled circuit.

If the internal pressure does not build up sufficiently rapidly to cause rupture of the tubular closure 3, it is possible that the low temperature fusible alloy 38 intermediate the lower plate 39 and the conducting member 28 will melt, thereby permitting the flexible conductor 27 to disengage the lower end of the cutout. The gas entrapped 25 within the cutout will then vent through the openings 33 and 43 which were previously occupied by the conducting member 28 and the alloy 38, and, due to the high velocity which results from the pressure within the device, will cause a 30 practically immediate extinction of any arc which might be formed due to the separation of the conducting member 28 and the lower conducting plate 38.

No particular vent passage is provided for causing 45 the gas formed during the interruption of heavy current overloads to vent through the central opening 33 in the lower portion of the insulating member 3 and the opening 43 in the conducting plate 38, the normal manufacturing in- 50 accuracies of these parts being sufficient to permit the gas to raise up the resistance plates 45 and flow therebetween.

It should also be noted that some gas will be evolved from the wax 48 during each operation of 55 the cutout, due to the heating effect of the resistance discs 45, but it is only upon the occurrence of moderate and large overloads that large gas pressures are developed within the device. As a result, the velocity and the volume of the 60 outflowing arc extinguishing gases are greatest when the cutout is required to open large over- loads.

It will thus be seen that I have disclosed a 65 novel form of circuit interrupter of the cutout type which is particularly suitable for use in protecting distribution transformers or other apparatus which may be mounted in an inaccessible place. My improved cutout includes means visible at a considerable distance for indicating when 70 the circuit has been opened due to operation of the device; it is simple in design, inexpensive to manufacture and may be installed in a short period of time with a minimum of effort. Moreover, my improved circuit interrupting device is 75 entirely supported upon one of the conductors of

the transmission line, thereby eliminating the necessity for any intermediate support means.

Further, I have disclosed a novel form of circuit interrupter which utilizes an explosive blast of arc extinguishing gas for interrupting a circuit, 5 my novel circuit interrupter being provided with a frangible closure and means whereby the closure may be broken during the operation of the device to effect the interruption of the controlled circuit. In effecting these novel results, I have 10 utilized an improved thermally-responsive heating element which is applicable to electrical apparatus generally.

While in accordance with the patent statutes, 15 I have disclosed the details of a preferred embodiment of my invention, it is to be understood that many of these details are merely illustrative and variations in their precise form will be both possible and necessary in some applications. I 20 desire, therefore, that my invention be limited only as set forth in the appended claims and by the prior art.

I claim as my invention:

1. In a circuit interrupter, means movable from a closed circuit position to an open circuit position to open the circuit, means biasing said movable means toward the open circuit position, current-carrying heater means, means responsive to the heating effect of said heater means for normally preventing said biasing means from causing said movable means to move from the closed circuit position to the open circuit position, and current-carrying electro-responsive means normally connected in parallel with said heater means for limiting the current flow in said heater means until the occurrence of predetermined conditions in the circuit controlled by said interrupter. 25

2. In a circuit interrupter, means biasing said interrupter to the open circuit position, a current-carrying heater means, means which normally prevents said biasing means from actuating said interrupter but which is operable in response to the heat produced by said heater means to allow said biasing means to cause said interrupter to move from the closed circuit position to the open circuit position, and a fusible element connected 45 in parallel with said heater means, said element fusing upon the occurrence of predetermined conditions to cause an increase in the heating effect 50 of said heater means.

3. In a circuit interrupter, means movable from a closed circuit position to an open circuit position to open the circuit, means biasing said movable means to the open circuit position, fusible 55 means for retaining said movable means in the closed circuit position against said biasing means, and current carrying heater means for causing said fusible means to release said movable means, thereby effecting the opening of the circuit controlled by said interrupter, said heater means comprising a resistance unit and a fusible element 60 electrically connected in parallel.

4. In a circuit interrupter, means movable from a closed circuit position to an open circuit position to open the circuit, means biasing said movable means to the open circuit position, thermally responsive means for retaining said movable means in the closed circuit position against said 65 biasing means, and current carrying heater means, comprising at least one substantially flat plate of non-metallic material thermally conductively joined to said thermally responsive means 70 for causing said interrupter to move to the open 75

circuit position upon the occurrence of predetermined conditions.

5. In a circuit interrupter, means movable from a closed circuit position to an open circuit position to open the electrical circuit through said interrupter, means biasing said movable means to the open circuit position, thermally responsive means comprising a means of fusible material for retaining said movable means in the closed circuit position against said biasing means, and current-carrying heater means, comprising at least one flat plate of non-metallic resistance material thermally conductively joined to said means of fusible material, for causing said interrupter to move to the open circuit position upon the occurrence of predetermined conditions.

6. In a circuit interrupter, a tubular means of insulating material having terminal means at either end and a section of reduced cross section intermediate said terminal means, said tubular means and said terminal means forming a substantially closed chamber, heat responsive means within said chamber for creating pressure therein, and heater means for said heat responsive means, comprising an electro-responsive element, operable upon the occurrence of predetermined conditions to cause sufficient pressure within said chamber to rupture said tube adjacent said section of reduced area and thereby open the circuit controlled by said interrupter.

7. In a circuit interrupter, means defining a chamber, at least a portion of the walls of which comprise insulating material having a sufficiently large coefficient of thermal expansion that local heating will cause said insulating material to break, and heater means positioned within said chamber adjacent said breakable portion and comprising an electro-responsive element operable upon the occurrence of predetermined conditions to cause sufficient local heating adjacent said portion to effect the breaking of said wall portion and thereby cause the opening of the circuit controlled by said interrupter.

8. In a circuit interrupter, a tubular means of insulating material having a sufficiently large coefficient of thermal expansion that local heating will cause said insulating material to break, metallic conducting means supported at either end of said tubular means, means biasing at least one of said conducting means away from the other of said conducting means, and heater means disposed within said tubular means and comprising an electro-responsive element operable upon the occurrence of predetermined conditions to cause sufficient local heating of a portion of said tubular means which is located intermediate said conducting means to break said tubular means, thereby permitting at least one of said conducting means to be moved by said biasing means to cause the opening of the circuit controlled by said interrupter.

9. In a circuit interrupter, a tubular means of insulating material having a sufficiently large coefficient of thermal expansion that local heating will cause said insulating material to break, metallic conducting means supported at either end of said tubular means, means biasing at least one of said conducting means away from the other of said conducting means, and heater means comprising at least one substantially flat plate of non-metallic resistance material which is adapted to be disposed within said tubular means in close proximity to the inner walls thereof, said heater means, upon the occurrence of predetermined conditions, causing sufficient

local heating of the adjacent portion of said tubular means to break said tubular means, thereby permitting at least one of said conducting means to be moved by said biasing means to cause the opening of the circuit controlled by said interrupter.

10. In a circuit interrupter, a tubular means at least partially of insulating material, metallic conducting means supported at either end of said tubular means, means biasing at least one of said metallic conducting means away from the other of said conducting means, a fusible means restraining said conducting means against said biasing means, and current carrying heater means for causing said fusible means to release said conducting means upon the occurrence of predetermined conditions, thereby permitting said biasing means to cause the opening of the circuit controlled by said interrupter, said heater means comprising at least one substantially flat plate of non-metallic resistance material disposed adjacent said fusible means.

11. In a circuit interrupter, a tubular means at least partially of insulating material, metallic conducting means supported at either end of said tubular means, means biasing at least one of said metallic conducting means away from the other of said conducting means, a fusible means for restraining said conducting means against said biasing means, and current carrying heater means for causing said fusible means to release said conducting means upon the occurrence of predetermined conditions thereby permitting said biasing means to cause the opening of the circuit controlled by said interrupter, said heater means including a current-carrying resistance means disposed adjacent said fusible means and a current carrying fusible element electrically connected in parallel with said resistance means.

12. In a circuit interrupter, a tubular means of insulating material, metallic conducting means affixed to one end of said tubular means, said conducting means including a single, unitary clamp means for engaging one of the conductors of a transmission line so as to electrically connect said conducting means to said conductor and to entirely support said interrupter on said conductor, a second conducting means supported at the other end of said tube, means biasing said second conducting means away from said first conducting means, fusible means within said tubular means for completing the electrical circuit between said conducting means disposed at either end thereof, said fusible means acting upon the occurrence of predetermined conditions to permit said biasing means to move said second conducting means away from said first conducting means, thereby opening the circuit controlled by said interrupter and causing the arc incident thereto to be established within said tubular means, and means, capable of liberating gas when placed in proximity to an electric arc, disposed within said tubular means for aiding in the extinction of said arc during each circuit opening operation.

13. In a circuit interrupter, a tubular means of insulating material, metallic conducting means affixed to one end of said tubular means, said conducting means including a single, unitary clamp means for engaging one of the conductors of a transmission line so as to electrically connect said conducting means to said conductor and to entirely support said interrupter on said conductor, a fusible current-carrying means at

least partially within said tubular means and electrically connected to said conducting means, a second conducting means supported on the other end of said tube through the agency of said 5 fusible means, said second conducting means including a flexible conductor for connecting said interrupter to the controlled equipment, the weight of said flexible conductor biasing said second conducting means away from said tubular means, said fusible means electrically connecting said two conducting means, restraining said second conducting means against movement as a result of the biasing action of the weight of said flexible conductor, and being adapted to release 10 said second conducting means upon the occurrence of predetermined conditions to cause the opening of the circuit controlled by said interrupter, and means capable of liberating gas when placed in proximity to an electric arc disposed within said tubular means for creating a pressure therein which aids in moving said second conducting means to the open circuit position during each circuit opening operation.

14. In electrical apparatus, a fusible element 25 for causing operation of said apparatus, and heater means for said fusible element comprising a current-carrying member of non-metallic resistance material and a second fusible element normally connected electrically in parallel with 30 said member.

15. In electrical apparatus, a fusible element for causing operation of said apparatus, and heater means for said fusible element, comprising a current-carrying member, of a material composed largely of carbon, for heating said element, and a second fusible element normally connected 35 in parallel with said current-carrying member.

16. In electrical apparatus, a fusible element for causing the operation of said apparatus, and 40 heater means for said fusible element comprising a current-carrying member, of a material composed largely of silicon carbide, for heating said element, and a second fusible element normally connected in parallel with said current-carrying 45 member.

17. In a circuit interrupter, a tubular means of insulating material having conducting means supported on either end thereof and having a section of reduced cross-sectional area intermediate said conducting means, said tubular means and said conducting means forming a substantially closed chamber, heat responsive means within said chamber for creating pressure therein, and electro-responsive heater means operable upon the occurrence of predetermined conditions 55 to cause said heat responsive means to generate sufficient pressure within said chamber to effect the rupture of said tubular means adjacent said portion of reduced cross-sectional area, the rupture of said tubular means allowing the pressure within the chamber to aid in effecting the separation of said conducting means.

18. In a circuit interrupter, a tubular means of insulating material having conducting means supported on either end thereof and having a section of reduced cross-sectional area intermediate said conducting means, said tubular means and said conducting means forming a substantially closed chamber, heat responsive means within said chamber for creating pressure therein, and electro-responsive heater means operable upon the occurrence of predetermined conditions to cause said heat responsive means to generate sufficient pressure within said chamber to 65 effect the rupture of said tubular means adjacent

said portion of reduced cross-sectional area, the rupture of said tubular means allowing the pressure within the chamber to aid in effecting the separation of said conducting means at high speed, said heat responsive means being of a material which evolves an arc extinguishing gas when heated in order that the arc which is established incident to the opening of the electrical circuit through said interrupter shall be subjected to a blast of arc extinguishing gas upon 10 the rupture of said tubular means.

19. In electrical apparatus, thermally responsive means operable when heated to effect the actuation of said apparatus, and a current-carrying heater means for said thermally responsive 15 means, comprising a solid member of non-metallic resistance material and an electro-responsive unit electrically connected in parallel therewith, said electro-responsive unit being operable upon the occurrence of predetermined conditions to 20 so change the normal division of current flow between said parallel paths that a substantially greater than normal portion of the current flows through said member of resistance material.

20. In electrical apparatus, thermally responsive means operable when heated to effect the actuation of said apparatus, and heating means for said thermally responsive means, comprising a solid member of non-metallic resistance material and an electro-responsive unit electrically 30 connected in parallel therewith, said electro-responsive unit being operable upon the occurrence of predetermined conditions to cause substantially all of the current flowing through said heater means to flow through said member of 35 resistance material.

21. In electrical apparatus, a thermally responsive means operable when heated a predetermined amount to effect the actuation of said apparatus, and current-carrying heating 40 means for said thermally responsive means, comprising a solid member of non-metallic resistance material and a fusible element electrically connected in parallel therewith, said element being fusible upon the occurrence of predetermined conditions to cause substantially all of the current flowing through said heater means to flow through said resistance member in order to maximize the heating effect thereof.

22. In a gas blast circuit interrupter, a tubular means of insulating material for defining the walls of an arc chamber, metallic conducting means affixed to one end of said tubular means, said conducting means including a single, unitary clamp for engaging one of the conductors of a transmission line so as to electrically connect said conducting means to that conductor and to entirely support said interrupter in a generally vertical position thereon, a second conducting means supported at the other end of 55 said tube, fusible means disposed within said arc chamber for completing the electrical circuit between said conducting means, said fusible means being automatically operable upon the occurrence of predetermined conditions to open the 60 electrical circuit through said interrupter and to establish the arc incident thereto within said arc chamber, and means for causing a blast of arc extinguishing gas to flow expulsively through said arc chamber during each operation of said 65 interrupter in order to effect the extinction of said arc, at least one end of said arc chamber being open at least during each operation of said interrupter.

23. In a gas blast circuit interrupter; a tubular 70

75

- means of insulating material for defining the walls of an arc chamber; a metallic conducting means affixed to the upper end of said tubular means; said conducting means being adapted to 5 close the upper end of the chamber defined by said tubular means and including a single, unitary clamp for engaging one of the conductors of a transmission line so as to electrically connect said conducting means to that conductor 10 and to entirely support said interrupter in a generally vertical position thereon; a second conducting means supported at the other end of said tube, which end is open at least during each operation of said interrupter; conducting means 15 disposed within said arc chamber for completing the electrical circuit between said conducting means positioned at either end of said tubular means which defines the walls of said chamber; said conducting means including a fusible 20 element, means of conducting material movable upon the fusion of said element to open the electrical circuit through said interrupter and to establish the arc incident thereto within said arc passage, and means biasing said conducting 25 means to the open circuit position; and means for causing a blast of arc extinguishing gas to flow expulsively through said arc chamber during each operation of said interrupter to effect the extinction of said arc.
- 30 24. In a circuit interrupter, conducting means movable from a closed circuit position where it completes the electrical circuit through the circuit interrupter to an open circuit position to open the electrical circuit, means biasing said 35 movable conducting means to the open circuit position, a fusible portion in said electrical circuit for normally retaining said movable conducting means in said closed circuit position against the force exerted by said biasing means, 40 said fusible portion when melted causing the electrical circuit to be interrupted and the arc to be drawn at the point where it melts, and current carrying heater means comprising one or more substantially flat plates of carbonaceous 45 resistance material having a fixed resistance, thermally conductively joined to said fusible portion for effecting the operation of said interrupter upon the occurrence of predetermined conditions.
- 50 25. In a circuit interrupter, conducting means movable from a closed circuit position where it completes the electrical circuit through the circuit interrupter to an open circuit position to open the electrical circuit through said 55 interrupter, means biasing said movable conducting means to the open circuit position, a fusible portion in said electrical circuit for normally retaining said movable conducting means in said closed circuit position against said biasing means, 60 said fusible portion when melted causing the electrical circuit to be interrupted and the arc to be drawn at the point where it melts, current carrying heater means comprising one or more substantially flat plates of resistance material 65 having a fixed resistance, thermally conductively joined to said fusible portion for effecting the operation of said interrupter upon the occurrence of predetermined conditions, and means for electrically connecting said heater means 70 into current responsive relationship with the electrical circuit through said interrupter, said conducting means being so arranged that the electrical current flows through said plate in a direction substantially coinciding with its least 75 dimension.

26. In an expulsion circuit interrupter, a tubular member of insulating material, conducting means mounted on said tubular member of insulating material adjacent one end thereof, a line conductor for supporting the circuit interrupter, said conducting means adjacent one end of the tubular member including a readily detachable clamp for making electrical connection to said line conductor and suspending said tubular member therefrom in a generally vertical 10 position, a second conducting means at the other end of said tubular member, fusible means disposed within said tubular member for completing the electrical circuit between said conducting means, said fusible means being automatically 15 operable upon the occurrence of predetermined conditions to cause opening of the electrical circuit through the interrupter and to establish the arc incident thereto with at least one end of the arc within said tubular member, one end 20 of said tubular member being open during the operation of the circuit interrupter, and the interior of said tubular member having means for evolving gas when acted upon by the arc to cause an expulsive flow of gas out said open end of 25 the tubular member to aid in extinguishing the arc.

27. In an expulsion circuit interrupter, a tubular member of insulating material, conducting means mounted on the end of said tubular member of insulating material, said conducting means closing one end of said tubular member and including a screw-operated clamp readily engageable with and disengageable from a line conductor, said clamp electrically connecting said 30 conducting means to the line conductor and holding said tubular member suspended from the line conductor in a generally vertical position and being the sole support for said tubular member, a second conducting means at the other end of 35 said tubular member, a fusible portion disposed within said tubular member for completing the electrical circuit between said conducting means at the ends of the tubular member, said fusible portion causing the opening of the circuit interrupter upon the occurrence of an overload current and establishing the arc incident thereto with at least one end in said tubular member, means biasing the melted parts of said fusible 40 portion to separate and lengthen the arc, and the interior of said tubular member including means which when acted upon by the arc gives off gas to flow expulsively out the open end of said tubular member and aid in extinguishing the arc.

28. In an expulsion circuit interrupter, a tubular member of insulating material, conducting means mounted on said tubular member of insulating material adjacent one end thereof, a line conductor for supporting the circuit interrupter, said conducting means adjacent one end of the 55 tubular member including a readily detachable clamp for making electrical connection to said line conductor and suspending said tubular member therefrom in a generally vertical position, a second conducting means at the other end of 60 said tubular member, a second line conductor connected to said second conducting means, fusible means disposed within said tubular member for completing the electrical circuit between said 65 conducting means, said fusible means being automatically operable upon the occurrence of predetermined conditions to cause opening of the electrical circuit through the interrupter and to establish the arc incident thereto with at least one end of the arc within said tubular member, 70

one end of said tubular member being open during the operation of the circuit interrupter, and the interior of said tubular member having means for evolving gas when acted upon by the arc to cause an explosive flow of gas out said open end of the tubular member to aid in extinguishing the arc, and said operation of the circuit interrupter causing said second line conductor to be disconnected from said tubular member of insulating material thereby relieving said tubular member of the voltage between said line conductors.

29. In a high tension expulsion circuit interrupter, a tubular member of insulating material, 15 conducting means mounted on said tubular member of insulating material adjacent one end thereof, a line conductor for supporting the circuit interrupter, said conducting means adjacent one end of the tubular member closing said end of 20 the tubular member and including a readily detachable clamp for making electrical connection to said line conductor and suspending said tu-

bular member therefrom in a generally vertical position, said readily detachable clamp securely fastening the circuit interrupter in place on the line conductor and holding it there during the expulsion action of the interrupter, a second conducting means at the other end of said tubular member, fusible means disposed within said tubular member for completing the electrical circuit between said conducting means, said fusible means being automatically operable upon the 10 occurrence of predetermined conditions to cause opening of the electrical circuit through the interrupter and to establish the arc incident thereto with at least one end of the arc within said tubular member, the other end of said tubular 15 member being open during the operation of the circuit interrupter, and the interior of said tubular member having means for evolving gas when acted upon by the arc to cause an explosive flow of gas out said open end of the tubular member 20 to aid in extinguishing the arc.

EDWARD F. BECK.
